COMBINATION CARBONATING AND BOTTLE
FILLING MACHINE

William E. Bostelmann, Elmwood Park, Ill.

Application April 13, 1936, Serial No. 74,095

4 Claims. (Cl. 226—69)

This invention relates to an improved combination carbonating and bottle filling machine, and has, for one of its principal objects, the provision of a unitary structure which shall combine the features of a liquid carbonating mechanism and a bottle filling device.

One of the important objects of this invention is to produce, in a single mechanism, a combined means for charging water with carbon dioxide, and also include in the apparatus, a bottle filling mechanism, whereby plain clear water can be taken into a single apparatus and delivered to the bottles in properly charged condition.

Other objects of the invention will consist in novel arrangements of parts and combination of mechanisms which will produce an efficient and workable apparatus of the class described.

Other and further important objects of the invention will be apparent from the disclosures in the accompanying drawing and following specification.

The invention, in a preferred form, is shown in the drawing and hereinafter more fully described.

25 In the drawing:

The figure is a vertical sectional view of the improved combination carbonating and bottle filling device of this invention, showing a preferred embodiment thereof.

30 As shown in the drawing:

The reference numeral 10 indicates generally an intake pipe for plain pure water which is to be used in the beverages carbonated and bottled by the apparatus of this invention.

35 Mounted about the pipe 10 is a rotatable support 12 which is, in turn, supported and which can be operated by any suitable means and mechanism common in the art.

40 Mounted on the support 12 is an upright 14 in the form of a hollow tube or the like which supports the combination carbonating and liquid supply chamber 16.

45 Also mounted on the support 12 is a motor 18 which operates a pump 20, the pump having an intake pipe 22 which is rotatably fitted over the upper end of the pipe 10 and which pipe is provided with a check valve 24. The pump also is fitted with a discharge pipe 26 having a corresponding check valve 28, and this pipe 26 extends 50 upwardly into and almost to the top of the carbonating chamber 16, having fitted into the upper end thereof a deflector cap 30 supported by spaced bracket elements 32. Suitable packing glands 34 and 36 are provided around the 55 pipes 10 and 26 to prevent leakage.

Mounted on the intake pipe 26 and extending through the upper area of the carbonating chamber 16 is a plurality of baffle plates 38 as is usual in these carbonating devices, and beneath the baffle plates 38 is a space where the charged 5 water collects, the level of the same being regulated by means of a float 40. This float is connected to a switch device 42 which controls the operation of the motor 18, and the float also controls the operation of the usual snifter or 10 excess air elimination tube 44.

Fitted into the top of the carbonating chamber 16 is an inlet pipe 46 through which the carbon dioxide gas is introduced into the chamber, the pipe 46 following the top and side of 15 the chamber and thence inwardly under the baffles 38 into the pipe 26 where it is provided with an upwardly-turned discharge end as shown at 48.

The upper end of the pipe 46 is provided with the usual fitting 50 in which it rotates, and 20 mounted in the fitting is a gas inlet pipe 52.

In this manner, the entire device will be enabled to rotate with the exception of the water intake pipe 10 at the bottom of the structure and the gas intake pipe 52 at the top of the 25 structure.

Also mounted in and connected with the carbonating chamber 16 are the usual bottle filling devices, comprising essentially a gas discharge tube 54 which terminates near the top of the 30 chamber and thence leads downwardly and finally outwardly through a valve-supporting arm 56 on the end of which is mounted the usual bottle filling valve structure 58.

As is usual in these bottle filling devices, other 35 valve-supporting arms 60 are provided having passages 62 therethrough for the discharge of properly carbonated liquid therethrough, the same being also controlled by a valve 58. There is a tube 54 and a passage 62 in each and every 40 arm 56 or 60.

It will be evident that herein is provided a combination water charging and bottle filling device which will eliminate the necessity of separate and expensive equipment which has heretofore been considered necessary in the preparation and bottling of carbonated beverages, and by the use of apparatus such as this, the gas lost due to the preliminary charging of water in one mechanism and the subsequent piping of this charged water to a bottle filling apparatus will be avoided.

Furthermore, a more compact and consequently more efficient device will immediately result,

and a considerably less cost for this apparatus will be experienced.

I am aware that many changes may be made throughout a wide range without departing from the principles of this invention, and I, therefore, do not purpose limiting the patent granted hereon otherwise than as necessitated by the prior art.

10 I claim as my invention:

1. A combination liquid carbonating and bottle filling mechanism, including a filling head, a fixed intake therefor for uncharged water, and a combined carbonating and bottle filling mechanism forming part of the filling head and rotatably mounted on the intake, the mechanism including a water pump and pipe line, and further means for introducing carbon dioxide into the pipe line beyond the pump and within the 20 filling head.

2. A combination liquid carbonating and bottle filling mechanism, including a fixed intake pipe for uncharged water, and a combined carbonating and bottle filling mechanism rotatably mounted thereon with the pipe as an axis, the mechanism including a water pump and an extension of the fixed intake pipe in the rotatable mechanism, said extension rotatable therewith,

and further means for introducing carbon dioxide into the water pipe beyond the pump, said means including a fixed gas intake pipe and a gas charging pipe rotatably mounted in the end of the gas intake pipe.

3. A combination liquid carbonating and bottle filling mechanism, including a fixed inlet pipe for uncharged water, and a combined carbonating and bottle filling mechanism rotatably mounted on the pipe, the mechanism including a chamber, 10 a water pump rotatable with the chamber, an extension of the water inlet pipe in the chamber and means for introducing carbon dioxide into the water pipe extension, said means including a fixed gas intake pipe and a gas charging pipe 15 rotatably mounted in the end of the fixed pipe, said connection being at the top of the entire mechanism and further means in the chamber to enhance gas absorption.

4. A combination carbonating and bottle filling mechanism, including a fixed liquid intake pipe, a carbonating chamber rotatably mounted thereon, and means for introducing liquid and carbon dioxide into the chamber, said means including a motor and pump for the liquid below 25 the chamber and rotatable therewith.

WILLIAM E. BOSTELMANN.
